US00D850892S

(12) **United States Design Patent** (10) **Patent No.:** **US D850,892 S**
(45) **Date of Patent:** **** Jun. 11, 2019**

(54) **MOUNTING BRACKET**

(71) Applicant: **Yen-Cheng Lin**, Taichung (TW)

(72) Inventor: **Yen-Cheng Lin**, Taichung (TW)

(**) Term: **15 Years**

(21) Appl. No.: **29/637,970**

(22) Filed: **Feb. 23, 2018**

(51) **LOC (11) Cl.** **08-05**

(52) **U.S. Cl.**

USPC **D8/373**

(57) **CLAIM**

The ornamental design for a mounting bracket, as shown.

DESCRIPTION

FIG. 1 is a perspective view of a mounting bracket according to a first embodiment of the present design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view of the first embodiment of the present design;

FIG. 9 is a perspective view of the mounting bracket according to a second embodiment of the present design;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof; and,

FIG. 16 is another perspective view of the second embodiment of the present design.
